(57) **CLAIM**

The ornamental design for a housing for an electrical connector, as shown and described.

DESCRIPTION

The present application is related by subject matter to U.S. Design patent application Ser. No. 29/393,276 entitled "Electrical Connector" filed on Jun. 1, 2011, U.S. Design patent application Ser. No. 29/393,280 entitled "Electrical Connector" filed on Jun. 1, 2011, and U.S. Design patent application 29/407,363 entitled "Housing for Electrical Connector" on Nov. 28, 2011.

FIG. 1 is a top, right, front perspective view of a housing for an electrical connector showing our new design;

FIG. 2 is a bottom, left, rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broke line portion of the figure drawings is included to show unclaimed subject matter only and forms no part of the claimed design. The dot-dash line in the figure drawings represents the boundary of the claimed design.

In a preferred embodiment, the nature of this product is a housing for supporting electrical terminals of an electrical connector that are configured for electrically connecting to an electrical device.
